CLAIM

The ornamental design for a hook-and-loop fastener for a face mask, as shown and described.

DESCRIPTION

FIG. 1 is an upper perspective view of a hook-and-loop fastener for a face mask showing our new design;

FIG. 2 is an upper perspective view thereof;

FIG. 3 is a front elevational view thereof;

FIG. 4 is a left side elevational view thereof, the right side being a mirror image;

FIG. 5 is a rear elevational view thereof;

FIG. 6 is a top plan view thereof; and,

FIG. 7 is a bottom plan view thereof.

The broken lines shown in FIG. 1 represent a face mask and a hook-and-loop fastener patch that form no part of the claimed design.
